UNITED STATES PATENT OFFICE.

PETER KERR, ALBERT J. BAUMANN, AND ADAM J. SHANKS, OF PORTLAND, OREGON.

GRAIN-HULLER.

No. 862,975.

Specification of Letters Patent.

Patented Aug. 13, 1907.

Application filed January 18, 1907. Serial No. 352,985.

To all whom it may concern:

Be it known that we, PETER KERR, a citizen of Great Britain, and ALBERT J. BAUMANN and ADAM J. SHANKS, both citizens of the United States, residing 5 at Portland, in the county of Multnomah and State of Oregon, have invented certain new and useful Improvements in Grain-Hullers; and we do hereby declare the following to be a full, clear, and exact description of the invention, such as will enable others skilled 10 in the art to which it appertains to make and use the same.

Our invention relates to improvements in grain hulling and cleaning machines, particularly oats, to prepare them for use in the manufacture of the higher 15 grades of oat food products.

The objects of our improvements are to provide a machine adapted to clean and remove the hulls from the oats or other grain; to separate the said hulls and all trash and dust from the cleaned grains leaving the grains 20 broken as little as possible; the said machine to have its parts adjustable to grains of different sizes and to compensate for any wear upon the abrading portions subject to wear by friction. We attain these objects by the mechanism illustrated in the accompanying drawings 25 in which

Figure 1 is a side elevation, part in section, and having the inclosing screen 12 partly cut away to show the interior. Fig. 2 is a sectional plan on the lines A A of Fig. 1. Fig. 3 is a detail showing means of adjusting.

On the shaft 1 are mounted a drive pulley 2 and spiders 3 and 4. The shaft 1 rotates in bearings 5 and 6, secured to the frame 7. The bearing 6 is integral with a plate 8 which inclose tightly the top of the machine. The lower portion of the machine is also inclosed by a plate 9. Resting against flanges 10 and 11 of the plates 8 and 9 and completely encircling the same is a perforated sheet metal cylinder 12, to the inside surface of which are secured in positions parallel to the axis of the shaft 1 long narrow strips 13 of metal or other 35 suitable material.

Adjustably mounted on the spiders 3 and 4 in positions parallel to the axis of the shaft 1 are ribbed metal plates 14 containing on their faces ribs 15 and brushes or knobs 16. The plates 14 are made adjustable on 45 their mountings by means of the set screws 17, Fig. 3, thereby enabling a variation of the clearance between the strips 13 and ribs 15. On the spiders 3 and 4 are also mounted the plates or wipers 18.

In the center of the plate 9 is an opening bounded by 50 a flange 19 which is in close contact with a flange 20 on the spider 3.

In an opening in the plate 8 is inserted the end of a feed spout 21 leading from the hopper. Immediately adjacent to the under side of the plate 9 is a space 22 inclosed by the walls 23 and from which leads a spout 24 55 to an exhaust fan. Connected with an opening in the plate 9 is a spout 25. In the plate 9 are openings 26 outside of the cylinder 12 and leading into the chamber 22. Walls 27 inserted in the frame 7 completely inclose the cylinder 12.

The operation of the machine is as follows:—Foreign matter, light grain and chaff are removed from the stock by well known methods before its introduction into the machine. The shaft carrying the spiders 3 and 4, and other attached parts, is rapidly rotated in the direction 65 shown by the arrow. The grain is fed in through the spout 21 falling into the cup-shaped portion of the spider 4 from which it is thrown by centrifugal force and falls into the space between the plates 14 and cylinder 12. Here the slats 13 obstruct the tendency of the air 70 to rotate with the wipers 18 and break it up into whirlpools, thus whirling the grain in its descent and partly holding it in suspension while the ribs 15 and brushes 16 are striking it forcibly in its various positions, by which means the hull is loosened and removed, together with all dirt and dust, but without breaking or 75 injuring the grain. The grain is not fed rapidly enough to pack in the machine but only fast enough to permit of its being held in suspension by the whirling of the air during its fall to secure the desired results without 80 breaking the grain, after which the grain and hulls fall onto the plate 9 and pass out through the spout 25 into suitable separating and cleaning machinery. A part of the dust and finer material passes through the perforated cylinder 12 and holes 26, and a part through the 85 opening in center of plate 9. The exhaust pressure through the spout 24 and the size of opening 26 in the plate 9 are so arranged as to give the desired speed of fall of the grain through the machine.

What we claim as our invention and desire to secure 90 by Letters Patent is—

1. In a device of the class described, a rotating member comprising an axle shaft, spaced heads carried by the shaft, plates extending between and connecting the heads and disposed substantially parallel with the shaft, means 95 to adjust the interval between the plates and shaft, a rib extending longitudinally of the plate, and spaced projections formed upon the plate upon opposite sides of the rib.

2. In a device of the class described, a rotating member comprising an axial shaft carrying spaced heads, plates secured to the heads and in substantial parallelism means to vary the intervals between the shaft and the plates, a rib extending longitudinally and centrally of each plate, 100 projections formed upon the plate upon opposite sides

of the rib, a casing inclosing the rotating member, and ribs formed upon the interior surface of the casing.

3. In a device of the class described, a rotating member comprising an axial shaft carrying spaced heads, plates secured to the periphery of the heads and in substantial parallelism with the shaft, means to vary the intervals between the shaft and the plates at opposite ends independently, a rib extending longitudinally and centrally of each plate, projections formed upon the plates upon opposite sides of the rib and extending away from the shaft, a perforated casing inclosing the rotating member, and

ribs formed upon the interior surface of the casing and extending toward the rotating members.

In testimony whereof we hereunto affix our signature, in presence of two witnesses.

PETER KERR.
ALBERT J. BAUMANN.
ADAM J. SHANKS.
